Primary Examiner — Justin M Jonaitis*Assistant Examiner* — Natalya M Rapundalo(57) **CLAIM**

The ornamental design for a couch cup holder tray as shown and described.

DESCRIPTION

FIG. 1 is a perspective view of a couch cup holder tray showing my new design;

FIG. 2 is another perspective view thereof;

FIG. 3 is a third perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The dash-dash broken lines in the drawings are for the purpose of illustrating portions of the couch cup holder tray that form no part of the claimed design.

1 Claim, 9 Drawing Sheets(56)
